UNITED STATES PATENT OFFICE.

PAUL LEHMANN, OF BERLIN, GERMANY.

AUTOMATIC GAS-IGNITION DEVICE.

SPECIFICATION forming part of Letters Patent No. 691,280, dated January 14, 1902.

Application filed September 5, 1901. Serial No. 74,574. (No model.)

To all whom it may concern:

Be it known that I, PAUL LEHMANN, chemist and engineer, a subject of the Emperor of Germany, residing at Wilhelmstrasse 40^a, Berlin, Germany, have invented new and useful Improvements in or Relating to Automatic Gas-Ignition Devices, of which the following is a specification.

My invention relates to automatic gas-ignition devices and is illustrated in the accompanying drawings, in which—

Figure 1 is a vertical section through the upper part of a chimney provided with my new ignition device. Fig. 2 is a top view of the same. Fig. 3 is a side view of the ignition device. Figs. 4 to 6 show a modification of my ignition device. Figs. 7 to 9 show other modifications of the device.

It has been usually assumed up to the present time that on opening the tap of an incandescent-light burner provided with a chimney the space in the latter is uniformly filled with an explosive mixture of gas and air. According to careful researches made by me this is, however, found not to be the case; but a comparatively small, narrow, and limited space is found in the chimney in which the mixture of gas and air is of such a nature that a chemical lighting mass can be brought to a glowing state and the gas ignited. With a newly-mounted evenly-formed incandescent mantle, with a vertical mantle-support, and normal burner the above-mentioned space will lie in the center of the chimney. These conditions are, however, seldom met with, and the shape of the incandescent body, the inclined position of the support, and differences in burners necessitate a considerable variation in the position and form of the explosive-gas air-zone suitable for automatic chemical lighters. Experiments have shown that very often more than half the space inclosed by the chimney is quite without an effective mixture of gas and air, so that an ignition-ball hanging in this part is not even warmed and far less brought to a glowing state. These facts give the reason why automatic gas-lighters provided even with good lighting material so often do not answer their purpose. With the aid of the present apparatus the ignition ball or device can with great facility be brought

into the proper zone, so as to make the ignition absolutely sure.

According to this invention upon the chimney is placed a narrow cross-bar *a*, provided with numerous recesses arranged closely together. This cross-bar may be in the form of a corrugated or notched strip of metal or a notched or screw rod or the like, and it can be attached on the upper margin of the chimney by any suitable means. Upon this bar is suspended, by means of a hook or an eye *b*, a carrier *B*, in which the ignition-ball *d* is hung. This carrier is provided with a handle *c*, by which it can easily be moved from one point to another along the bar. By this means the place can easily be found which is most suitable for the ignition. A circular or other shaped guard-plate *e* may be secured to the bottom of the carrier *B*, beneath the ignition-ball *d*, to prevent overheating of it while the burner is alight. It remains quite black, while the flame is alight, thus insuring a very long durability and efficiency of the lighting device. At the same time the plate prevents the falling down of platinum particles upon the mantle, where the same, in combination with thorium-oxid even in small quantities, would form large spots upon the mantle, which in burning would remain dark red, thereby affecting the intensity of the light.

The described arrangement can be also applied to a modified form of mantle-support provided with prongs at the top, as shown in the modified form, Figs. 4 to 6. In this case the guard-plate *e* rests, by means of two holes, upon the two prongs *f* of the mantle-supporting pin *g*, and the ignition-ball is supported above the plate, the cross-bar *a* being connected to the guard by a bend. In this case either the ignition-device support has a number of notches or the like for its adjustment or the adjustability can be effected by providing the base-plate with a number of holes, so as to adjust it as desired upon the prongs *f* of the pin *g*. This pin may have convenient projections for carrying the plate.

In the modification shown in Figs. 7 to 9 of the drawings the cross-bar *a* is adjustable in its holder *h*. This holder is provided with a headpiece *k*, having a hole *l*, in which the cross-bar *a* is inserted. After adjusting the

cross-bar so that the ignition-ball is in its proper position for ignition the cross-bar may be clamped by the screw *m*. The headpiece may be swung around on a pin of the holder *h* 5 and clamped thereon by a screw *i*. In the modification shown in Figs. 8 and 9 the cross-bar is provided with holes *m*, by which it may be brought upon a pin of the holder. In this case the bar after adjustment may be fixed to 10 the holder by a screw *o*.

I may mention that it is found very useful to inclose the carrier for the ignition-ball by a wire-gauze cage, such as shown in Fig. 7 of the drawings.

15 Having now particularly described and ascertained the nature of my said invention and in which manner the same may be performed, I declare that what I claim is—

1. In an automatic gas-ignition device, the 20 combination with an ignition-ball; of a carrier comprising a frame for holding said ball, a plate forming the bottom of said frame, and an eye for supporting said frame, substantially as described.

25 2. In an automatic gas-ignition device, the combination with a cross-bar; of a carrier suspended from said bar, and adjustable thereon, and an ignition-ball in said carrier, substantially as described.

30 3. In an automatic gas-ignition device, the combination with a cross-bar; of a carrier having an eye adjustable on said bar, and an ignition-ball in said carrier, substantially as described.

35 4. In an automatic gas-ignition device, the combination with a cross-bar; of a carrier adjustable on said bar, an ignition-ball in said carrier, and a handle on said carrier, substantially as described.

40 5. In an automatic gas-ignition device, the combination with a carrier comprising a frame, a plate forming the bottom of said frame and an eye for supporting said frame, and an ignition-ball in said frame; of a cross-bar passing through said eye and supporting said carrier, substantially as described.

6. In an automatic gas-ignition device, the combination with a cross-bar; of an ignition-ball, a carrier for the ignition-ball comprising a frame for holding said ball and an eye supporting said carrier adjustably on said bar, and a plate below said carrier, substantially as described.

7. In an automatic gas-ignition device, the combination with a cross-bar; of an ignition-ball, a carrier for the said ignition-ball, adjustable on said bar, and a plate below said carrier, substantially as described.

8. In an automatic gas-ignition device, the combination with a carrier comprising a frame 60 and an eye, and an ignition-ball in said carrier; of a cross-bar passing through said eye and having means for retaining said carrier in any desired position thereon, substantially as described.

9. In an automatic gas-ignition device, the combination with a carrier comprising a frame and an eye, and an ignition-ball in said carrier; of a cross-bar passing through said eye and means for adjusting said bar, substantially as described.

10. In an automatic gas-ignition device, the combination with a carrier comprising a frame and an eye, and an ignition-ball in said carrier; of a cross-bar passing through said eye, 75 and means for holding said bar on the top of a lamp-chimney, substantially as described.

11. In an automatic gas-ignition device, the combination with a carrier comprising a frame and an eye, and an ignition-ball in said carrier; of a cross-bar passing through said eye, means for holding said bar on the top of a lamp-chimney, and means for adjusting its 80 position in relation thereto, substantially as described.

In testimony whereof I have signed my name to this specification in the presence of two subscribing witnesses.

PAUL LEHMANN.
